Fig.1.

Fig.2.

Fig.3.

Fig.4.

FIG. 1 is a top plan view of a pair of safety spectacles showing my new design shown in partially non-operating condition;

FIG. 2 is a front view thereof;

FIG. 3 is a rear view thereof; and

FIG. 4 is a side view thereof as viewed from the left of FIG. 3.

The temples are shown broken away in FIG. 2 and omitted in FIG. 3 for convenience of illustration.

My design for the safety spectacles disclosed is characterized by the front portion of said spectacles, including the ornamental hinge portion, having the configuration as shown.

I claim:

The ornamental design for a pair of safety spectacles, substantially as shown and described.
